SCRUBBING BRUSH WITH SOAP SUPPLY

Sophia Swartz, New York, N. Y.

Application April 6, 1949, Serial No. 85,785

3 Claims. (Cl. 15—122)

1

My invention relates to improvements in scrub brushes, and more particularly to a brush which is provided with means for containing and dispensing soap.

The principal object of my invention is the provision of a scrub brush which contains a porous receptacle for soap and which will produce suds by merely applying water thereto. A brush of this type is particularly advantageous in washing tableware, for which it is customary to employ a dishrag for china and glassware, and a stiff brush or steelwool pad for pots and pans. Both of the aforementioned types of utensils must be separately applied to soap during the course of the dishwashing, which is time consuming and inconvenient. My invention may also be applied to brushes of other types, such as those used for cleaning sinks, bathtubs, toilet bowls, walls, and the like, with equally advantageous results.

Another object of the invention is the provision of a brush of the character described which will hold and dispense cleaning agents of all types, such as bars of soap, soap flakes, soap powder, scraps of soap bars, etc.

Still another object of my invention is the provision of a scrubbing brush which is especially adapted for dish-washing in that the advantages of a dish cloth and stiff brush are combined in one utensil.

A further object of the invention is the provision of a brush of the character described which is made of a minimum of parts, is extremely economical to manufacture, and which can be adapted for almost every household washing use.

Other objects and advantages of my invention will be readily apparent in the course of the following specification when taken in connection with the accompanying drawings, in which:

Fig. 1 is a top plan view of a dish-brush embodying my invention, a portion of the brush bristles being cut away to reveal the means for attachment of the soap container.

Fig. 2 is a side elevation of the brush shown in Fig. 1.

Fig. 3 is an enlarged plan view showing a portion of the soap container attached to the wire frame of the brush in a different manner.

Fig. 4 is a sectional view, taken along line 4—4 of Fig. 3 on a still larger scale.

Fig. 5 is a plan view of a brush incorporating another type of soap container, which container is attached to the brush by the fastening means shown in Figs. 3 and 4. In this view, the vertical bristles of the brush are not shown.

Fig. 6 is a side elevation of the brush shown in Fig. 5, with portions of the bristles being omitted to more clearly reveal the construction of the soap container and wire frame.

Figs. 1 and 2 show a dish brush provided with a soap container of my invention. The brush 10 is of the conventional type used for washing

2

dishes, and comprises a handle 11, a wire frame 12, and tufts of stiff bristles 13 which protrude from the frame 12 in both vertical and horizontal directions.

The wire frame 12 is of the usual type, comprising a pair of thick wires twisted about each other to form a series of closely disposed spiral convolutions 14. The ends of the wires are secured to the brush handle 11, the unattached portion of the frame 12 forming a loop 15. A tuft of bristles 13 is set with the space formed between each of the convolutions 14, the tension of the twisted wires comprising the frame 12 being sufficient to rigidly hold said bristles.

A soap container 16 is secured to brush 10 within the confines of the loop 15 formed by the wire frame 12. Said container 16 is in the form of a bag or pouch which is shaped to fit snugly within said loop 15. Container 16 is preferably made of a loosely woven cloth such as that used in the manufacture of dish-cloths, which cloth is of a filterable quality. The container 16 has an open top side which is provided with a drawstring 17 or other suitable closure means.

Figs. 1 and 2 illustrate one method by which the container 16 may be secured in position within the loop 15 of wire frame 12. This may be done during the same operation in which the tufts of bristles 13 are set within said frame 12, or it may be done in a separate operation. As shown in Fig. 1, a portion 18 of the side edge of the container 16 is drawn through each of the openings formed by the convolution 14 of the wire frame. The tension of the twisted wires is again sufficient to securely hold container 16 in position. The container 16 may, however, be secured in position by any other convenient means of attachment, such as stitching, cementing, etc. For instance, the edges of the container may be wrapped around the wire frame 12, or staples or other fasteners may be employed, if desired.

When it is desired to fill the container 16, the drawstrings 17 are untied and loosened, and any desired amount of soap is inserted into the mouth of said container. Since container 16 is made of fabric, it will retain soap chips, flakes, powder, and detergent powder. Alternatively, it may be filled with a bar of soap, or scraps of soap from used bars which are normally difficult and inconvenient to use. In addition the use of soap scraps affords a substantial economy in household management. The use of chips, flakes and powder is made especially convenient since the housewife is not required to fill the sink with water to use these agents, a task which is especially tedious when there is a single article to wash.

To produce a quantity of suds for cleaning, it is only necessary for the user to dip the brush 10 in water and begin to scrub the dish. The

fabric covering of the container 16 itself serves the function of a dishcloth for cleaning china and glassware. The tufts of bristles 13 are beneficial in scrubbing pots and pans or for removing grease and stains from silverware.

On the other hand, should the housewife desire to employ a dish-pan in which to wash a large quantity of dishes, it is only necessary for her to stir the water in the dish-pan with the brush and a quantity of suds will be quickly formed.

The base of the handle 11 may be provided with a hole 19, by means of which the brush may be hung upon a hook or nail while not in use. Thus the brush and the container 16 may be left to dry, so that the contained soap may be used over and over and may be easily replenished with almost anything at hand. In place of the hole 19, a ring or similar means may be provided.

Figs. 3, 4, 5, and 6 show another embodiment of my invention in which a soap container 20 is attached to a different type of brush 21, but in the same position as the container 16 previously described. This brush 20 is of the type usually used for cleaning bathroom fixtures such as bathtubs, toilet bowls, or the like. The container 20 for this purpose is made of a more durable material than the container 16, such material preferably being rubber or soft plastic, although it is to be understood that any suitable material of this sort may be used. Container 20 is provided with a large number of minute holes of perforations 22 which are large enough to permit water to permeate the interior of said container 20. The upper side of said container 20 is provided with a slide fastener 23 or other suitable closure means, which enables the container to be filled with any form of soap or household detergent and re-sealed. The perforations 22 are sufficiently small to prevent soap chips or powder from leaking out of the container 20. The brush 21 is provided with a long handle 11a, so that it may be easily recognizable if a short-handled brush of the same type is used for dishes.

As clearly shown in Figs. 3 and 4, the container 20 may be secured to the wire frame 12a by a series of small wire loops or staples 24. Staples 24 extend through the wall of said container 20 and are secured about both wires of frame 12a, thus fixing container 20 firmly in position. The container 20 may, however, be secured to frame 12a in any other convenient or suitable means, such as heat-sealing, cementing, etc.

As was the case for brush 10, the brush 21 may be used for scrubbing by merely dipping it in water for a sufficient time in which the container 20 may become saturated. The scrubbing motion of the brush will cause the contained soap to extrude suds through the perforations 22 in the walls of container 20.

The container 20 is especially adapted for washing bathroom fixtures since the plastic or rubber walls of the container will not absorb dirt. In addition, the bristles of the brush are sufficiently spaced so that they may be easily rinsed.

While preferred embodiments of my invention have been shown and described herein, it is obvious that numerous omissions, alterations, and additions may be made in the invention without departing from the spirit and scope thereof. The description and drawings, therefore, are

meant to be taken in an illustrative, rather than a limiting sense.

I claim:

1. A scrubbing brush comprising a handle; a wire frame attached to said handle and bent in the form of a loop, bristles attached to said wire frame and extending upwardly, downwardly and outwardly therefrom, and a hollow soap container disposed within said loop and secured to said wire frame around the predominant portion of the periphery thereof, said container having walls made of a soft, flexible, water-permeable sheet material, said container also having an opening through which soap may be inserted, said opening being spaced from said wire frame, and closure means for said opening, the wall of said container opposite said closure means extending at least to the ends of the adjacent bristles.
2. A scrubbing brush comprising a handle, a wire frame attached to said handle and bent in the form of a loop, bristles attached to said wire frame and extending upwardly, downwardly, and outwardly therefrom, and a hollow soap container disposed within said loop and having walls made of a soft fabric sheet material defining a pouch, the side walls of said soap container being secured to said wire frame at closely-spaced intervals around the predominant portion of the periphery thereof, said container also having a central opening in its top wall through which soap may be inserted, and closure means for said opening, the bottom wall of said container extending downwardly at least to the bottom ends of the adjacent downwardly-extending bristles.
3. A scrubbing brush comprising a handle, a wire frame attached to said handle and formed of a pair of wires twisted around each other and bent in the form of a loop, bristles attached to said wire frame, and a soap container disposed within said loop and secured to said wire frame around the predominant portion of the periphery thereof, said container having walls made of a soft fabric sheet material portions of which are pulled through the twists of the wire frame to hold said container firmly in position within the loop, said container also having an opening through which soap may be inserted, said opening being centered in a wall of said container and being spaced from said wire frame, and closure means for said opening, the weave of said fabric constituting the container walls being sufficiently small to hold soap powder, the wall of said container opposite said closure means extending at least to the ends of the adjacent bristles.
